UNITED STATES PATENT OFFICE

WINFIELD R. DU BREUIL, OF CHICAGO, ILLINOIS.

AUTOMOBILE HEADLIGHT.

Application filed January 7, 1922, Serial No. 527,723. Renewed August 25, 1924.

To all whom it may concern:

Be it known that I, WINFIELD R. DU BREUIL, a citizen of the United States, residing at Chicago, in the county of Cook and State of Illinois, have invented certain new and useful Improvements in Automobile Headlights, of which the following is a specification.

My said invention relates to a projector intended primarily for use in headlights of automobiles and other moving vehicles but capable also of use in other relations. When used on moving vehicles an essential object of the invention is to prevent the blinding effect produced on pedestrians or drivers of approaching vehicles by the light from ordinary headlights. This is done by an arrangement of devices which permits the light to be thrown freely downward and forward at a level below the height of the eyes of approaching persons, the only rays of light which go higher being such as are transmitted through an opalescent or frosted screen whereby they are deprived of any blinding effect.

A further object of the invention is to provide a device of the character described which consists of few parts and is simple and inexpensive to manufacture.

Referring to the accompanying drawings which are made a part hereof and on which similar reference characters indicate similar parts,

Figure 1 is a plan view of the front portion of an automobile showing the location of the headlights,

Figure 2, a central vertical section, and

Figure 3 a front elevation of my device.

In the drawings reference character 10 indicates a lamp preferably an electric bulb of ordinary character, which is supported at the center of a reflector 11 of ordinary character and which may be so supported as to be adjustable with reference to the focus of the reflecting surface. The reflecting surface is preferably formed on a conical or parabolic shell and I preferably provide at the lower part of the shell a transverse shelf 12 to cut off the light from the lower part of the reflector. This shelf may, as here shown, form a part of the outer casing of the light, or may be set into the lower part of the reflector. In some cases I may also use a smaller shell having its lower edge at or near the bottom level of the casing.

The reflecting shell is positioned at the

rear end of a casing having an opening corresponding in size to the shell and the casing is or may be firmly fixed to the shell.

The casing in the form here shown consists of a rear housing 14 surrounding the shell 11, an upper part 13, forwardly extending side walls 15 and 16 flaring outwardly toward the front of the device and having each a horizontal lower edge and a downwardly sloping upper edge. The length of the side walls should be about three or four times the height of the reflector but in case a shelf is used as shown at 12 then the length of the wall will be three or four times the distance from the top of the shelf to the top of the reflector, these dimensions being preferred to secure a proper distribution of the light in a direction lengthwise of the road instead of a distribution over a wider area. The side walls are connected at the top by the downwardly sloping upper wall, the lower surface of which is a reflecting surface as are also the inner faces of the side walls. At the front of the device the side and top members are connected by a transverse member 18 soldered or otherwise attached to the side walls. A front window is left at 20 and this is closed by colored or frosted glass as here shown. In the use of my invention any glass or other device may be used for closing the window provided only that it transmit sufficient light to attract notice but shuts off any direct rays or any glaring light. The underside of the casing as here shown is open but may if desirable or necessary be closed by a sheet of plain glass.

The front of the casing may be rounded off so that the extremity of the window will be visible at the sides of the casing or if preferred a series of windows may extend across the rounded front of the casing. In this manner the attention of persons approaching from the sides of the machine will also be drawn thereto. Preferably, however, I leave the front of the casing straight and cut away the corners of the same to provide flat faces in which are set windows 21, similar to window 20. All of these windows are provided with colored or frosted glass or analogous material to prevent any undesirable glare.

Above the upper wall 13 I provide at the front of the casing a small light 22 which may serve as a parking light, and which may be of any desired type. It may be

operated in alternation with the main light by the usual two-way switch, or may be omitted if parking lights of different type are preferred, or if none are to be used.

5 The parking light is covered by a housing having a front wall 23 in which the lens 24 of the light is set, a top 25 and inclined parts 26 connecting the top to the front wall. Each headlight is preferably mounted on a ball and socket or other adjustable bracket 27 to permit proper location of the casing relative to the car.

From consideration of my invention as above described it will be seen that no direct rays of light are transmitted at such an angle as to be more than a safe distance above the highway, for example, about three feet, while at the same time owing to the relative positions of the light and 10 the reflector and to the angle of the lower edges of the side walls the light will be thrown forward to a distance of about two hundred feet or so depending on the strength of the source of illumination, this being sufficient for practical purposes in a headlight for moving vehicles, which is the main object of the invention. The light thrown from the lamp against the upper wall will be reflected downward and forward to the 15 road as also to a less extent will be the light from the side walls which as above shown are flared outwardly, the roof portion being somewhat fan-shaped and wider at the front than at the rear. The shelf 12 serves to cut off the rays of light from the lower portion of the reflector as these would otherwise be thrown upward higher than is desirable and the shelf is useful in that it enables the use 20 of a larger reflector than could be employed

if the entire surface of the reflector were utilized. 40

The windows at the front of the device serve to give warning to approaching pedestrians of the proximity of the vehicle and for this purpose are covered with colored or frosted glass or the like adapted to transmit light but to eliminate the glare and this material may be so selected as to subdue the light to any point desired. 45

It will be evident to those skilled in the art that certain modifications may be made in my device without departing from the spirit of the invention, the true scope of which is shown in the appended claim. 50

Having thus fully described my said invention, what I claim as new and desire to secure by Letters Patent, is: 55

In a headlight for vehicles, a source of illumination, a shell surrounding the same and having a reflecting surface, a shelf extending transversely of the lower portion of the shell, a casing extending over and forwardly of the shell, said casing having outwardly flaring side walls and a downwardly sloping upper wall whereby the light is reflected forwardly and downwardly and is prevented from rising higher than the source of illumination, substantially as set forth. 60

In witness whereof, I have hereunto set 70 my hand and seal at Washington, District of Columbia, this sixth day of January, A. D. nineteen hundred and twenty-two.

WINFIELD R. DU BREUIL.
